WIRE TWISTING TOOL

Raymond D. Anderson, Milwaukee, Wis.

Application June 14, 1943, Serial No. 490,815

4 Claims. (Cl. 140—120)

This invention relates to a wire twisting tool, and has for the primary object the provision of a tool of the above stated character which is especially adapted for twisting together strands of wire which have the ends thereof mounted or secured to a support and to permit the operation to be carried out with a maximum amount of safety to the operator and with a minimum amount of manual effort.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is an end elevation illustrating a wire twisting tool constructed in accordance with my invention.

Figure 2 is a vertical sectional view illustrating the tool with the strands of wire applied thereto.

Figure 3 is a fragmentary transverse sectional view showing the holder and the ratchet mechanism for the wire twisting element.

Figure 4 is a sectional view taken on the line 4—4 of Figure 3.

Figure 5 is a top plan view illustrating the wire twisting element.

Figure 6 is a perspective view illustrating a dog forming a part of the ratchet mechanism.

Figure 7 is a perspective view of a pin forming a part of the wire twisting mechanism.

Referring in detail to the drawings, the number 5 indicates the holder of the tool which consists of a substantially tubular shaped body 6 having a slot or entrance 7 formed in a wall thereof and extending the full length of the body. A tubular sleeve 8 is formed integrally with the body 6 opposite the entrance 7 and the bore thereof is partly screw threaded to have a handle 9 threaded therein. The bore enters the body of the holder and provides a mounting for a dog 10 spring influenced by a coil spring 11 interposed between the handle and the dog. Opposite walls of the sleeve are provided with slots 12 in which operates a pin 13 carried by the dog and provides means whereby the dog may be moved into a retracted position against the action of the spring 11.

The bore of the body has an internal shoulder 14 decreasing the diameter of a portion of the bore and in which is formed an annular groove or seat 15 to receive spring influenced detents 16

of a wire twisting element 17 capable of rotation within the bore of the body.

The wire twisting mechanism consists of a tubular body 18 provided with an external shoulder 19 to abut the shoulder 14 when the detents engage the seat. The body 18 is composed of half sections connected by a pivot pin 20 for hinging movement, the free ends of the sections being notched, as shown at 21. The body 18 has formed on its periphery ratchet type teeth 22 coaxing with the dog 10 in locking the body of the twisting mechanism to the body of the holder 5 when the handle 9 is swung in one direction and to permit the body of the holder to turn free 15 of the body of the twisting mechanism when the handle is swung in a reverse direction.

A pin 23 is apertured to receive the pin 20 and traverses the bore of the body 18 with its free end fitting in the notches 21.

20 In use the pin 23 is adapted to extend between supported wires 24, as shown in Figure 2, and by swinging the handle first in one direction and then in the other direction relative to the wires, said wires will be caused to twist about each 25 other with a maximum amount of safety to the operator and with a minimum amount of effort. Whenever it is desired to release the dog 10 from the ratchet teeth, the operator places pressure on the pin 13 in the direction of the handle.

30 To apply and remove the tool to the supported wires 24, the body 18 of the twisting mechanism is moved endwise from the body of the holder. The sections of the body 18 then may be swung apart so that the body 18 may be either placed 35 over or removed from the wire and when placed thereon the pin 23 extends between the wires. After the body 18 has been applied to the wires, the body 6 of the holder may be placed over the wires by permitting the wires to enter the body

40 by way of the entrance 7. The body 6 is then moved onto the body 18 of the twisting mechanism until the detents engage in the seat 15. The tool is then ready for operation on the wires to bring about the twisting of the wires together.

45 While I have shown and described the preferred embodiment of my invention, it will be understood that minor changes in construction, combination and arrangement of parts may be made without departing from the spirit and 50 scope of the invention as claimed.

Having thus described my invention, what I claim is:

1. In a wire twisting tool, a holder having a bore and an entrance to permit supported wires 55 to enter and leave the bore, a handle on the

holder, a twisting element journaled in the bore of the body and removable therefrom said twisting element being constructed of longitudinally split sections hingedly connected to each other at one longitudinal edge of the sections, and a ratchet mechanism connecting the twisting element to the holder.

2. In a wire twisting tool, a holder having a bore and an entrance to permit supported wires to enter and leave the bore, a tubular sleeve on the holder opposite the entrance, a handle secured in the sleeve, a spring influenced dog operable in the sleeve and extending into the bore, a twisting element journaled in the bore of the body and removable therefrom said twisting element being constructed of longitudinally split sections hingedly connected to each other at one longitudinal edge of the sections, and ratchet teeth formed on the twisting element and coacting with the dog.

3. In a wire twisting tool, a holder having a bore and an entrance to permit supported wires to enter and leave the bore, a sleeve formed on the holder opposite the entrance, a handle se-

cured in the sleeve, a spring influenced dog mounted in the sleeve and entering the bore, a longitudinally split sectional body journaled in the bore and removable therefrom, a pivot connecting one longitudinal edge of the sections to each other, ratchet teeth formed on the body and coacting with the dog, and a pin traversing the body.

4. In a wire twisting tool, a holder having a bore and an entrance to permit supported wires to enter and leave the bore, a sleeve formed on the holder opposite the entrance, a handle secured in the sleeve, a spring influenced dog mounted in the sleeve and entering the bore, a longitudinally split sectional body journaled in the bore and removable therefrom, a pivot connecting one longitudinal edge of the sections to each other, ratchet teeth formed on the body and coacting with the dog, said sections of the body having the free ends thereof notched, a twisting pin carried by the pivot and fitting in the notched ends of the body.

RAYMOND D. ANDERSON.
